UNITED STATES PATENT OFFICE.

JOHN HERBERT CHADWICK, OF GLENSIDE, PENNSYLVANIA, ASSIGNOR TO EDWARD F. MASON AND GEORGE N. SCHOFIELD, COPARTNERS TRADING AS SCHOFIELD, MASON & CO., OF PHILADELPHIA, PENNSYLVANIA.

DESIGN FOR A RUG.

43,756.

Specification for Design.

Patented Apr. 1, 1913.

Application filed February 20, 1913. Serial No. 749,732. Term of patent 7 years.

To all whom it may concern:

Be it known that I, JOHN HERBERT CHADWICK, a subject of the King of Great Britain and Ireland, residing at Glenside, Montgomery county, State of Pennsylvania, have invented a certain new, original, and ornamental Design for Rugs, of which the following is a specification, reference being had to the accompanying drawing, forming part thereof.

The figure is a plan view of a half section of a woven cotton bath rug, the other half section being identical therewith showing my new design.

I claim:—

The ornamental design for a rug, as shown.
JOHN HERBERT CHADWICK.
